UNITED STATES PATENT OFFICE.

JOHN HAUG, OF PHILADELPHIA, PENNSYLVANIA.

APPARATUS FOR COMPRESSING AND CHARGING COAL INTO COKE-OVENs.

SPECIFICATION forming part of Letters Patent No. 747,172, dated December 15, 1903.

Application filed November 15, 1902. Serial No. 131,492. (No model.)

To all whom it may concern:

Be it known that I, JOHN HAUG, a citizen of the United States, residing in the city and county of Philadelphia, State of Pennsylvania, have invented a new and useful Improvement in Apparatus for Compressing and Charging Coal for the Manufacture of Coke, of which the following is a specification.

My invention relates to improvements in apparatus for compressing and charging coal for the manufacture of coke; and it consists of means for compressing the coal placed in a compression-box and means for removing the sides of said box from contact with the coal therein, so as to permit the latter after being compressed to be easily removed from the compression-box.

It also consists of means for removing the compressed coal from the compression-box and directing the former into an oven.

It also consists of means for conveying the compression-box to any one of a series of ovens.

It further consists of means for forming the under side of the block of compressed coal with depressions to form passages through which the hot air, &c., in the ovens may circulate.

Figure 1 represents a partial side elevation and partial longitudinal vertical section of my improved apparatus for compressing and charging coal to be converted into coke. Fig. 2 represents a partial end elevation and partial transverse vertical section thereof.

Similar numerals of reference indicate corresponding parts in the figures.

Referring to the drawings, 1 designates a truck adapted to travel on the rails 2, so that said truck may be moved along the line of ovens 3 for a purpose hereinafter described.

Pivoted to the truck 1, as at 4, (see Fig. 2,) and at proper intervals are the sides 5 of the compression-box 6, which latter is provided at its forward end with a gate 7, hinged, as at 8, (see Fig. 1,) to the truck 1 and for a purpose hereinafter described.

Journaled in the truck 1 are sprocket-wheels 9, around which are passed sprocket-chains 10, to which is secured an endless apron 11, (see Fig. 2,) which is passed over rollers 12, journaled in the truck 1. The endless apron 11 has secured thereon a pusher

or plate 13, which also acts as the rear wall of the compression-box 6, as seen in Fig. 1.

Journaled in the truck 1 are eccentrics 14, 55 (see Fig. 2,) which are operated by the levers 15, so as to impart motion to the rods 16, which are pivoted, as at 17, to the sides 5 of the compression-box 6, so as to turn said sides 5 on their pivots 4 when required and 60 for a purpose hereinafter described.

Secured to a rod 18, journaled in the upper portion of the compression-box 6, (see Fig. 2,) are bridge-bars 19, from which depend toggle-levers 20, which are connected to a plate 21, 65 for a purpose hereinafter described.

22 designates a rod provided with right and left hand screw-threads 23, which engage screw-threaded blocks 24 in the toggle-levers 20 for the purpose of operating the latter, and 70 consequently the presser-plate 21. The rod 22 is provided with a hand-wheel 25 for the purpose of rotating said rod.

One or more of the bridge-bars 19 may have projecting therefrom a lever 26, to which is 75 connected one end of a chain, cord, &c., 27, which is wound around a drum 28 for the purpose of turning the rod 18, and consequently raising and lowering the bridge-bars 19, secured thereto, it being noted that the 80 latter are locked to the compression-box 6 when in the position seen in full lines in Fig. 2 by any suitable device, as at 29.

Located above the compression-box 6 are a series of bins 30, each of which is provided 85 with gates 31, which are opened and closed by any well-known mechanism.

The operation is as follows: The drum 28 is rotated by any suitable means and causes the chain, cord, &c., 27 to wind thereon, and 90 thus exert a pull upon the lever 26 in order to turn the bridge-bars 19 and cause the latter and the parts carried thereby to move out of the path of the coal discharged from a bin 30 and into the compression-box 6. The 95 compression-box 6 is brought beneath the discharge-opening of the bin 30 and the gates 31 are opened and permit the escape of coal from said bin, and when a sufficient quantity is discharged into the compression-box 6 the 100 gates 31 are closed to prevent the further escape of coal from the bin 30. The bridge-bars 19 and the parts carried thereby are then returned into their operative positions,

as seen in full lines in Fig. 2, after which said bridge-bars 19 are locked to the compression-box 6 by any suitable device—for instance, as indicated at 29 in Fig. 2. The hand-wheel 25 is then rotated, whereupon the right and left hand screw-threads 23 on the rod 22 will cause each pair of blocks 24 belonging to either of the toggle-levers 20 to move in opposite directions relatively to each other, it being apparent that when said rod 22 is turned in one direction it causes the toggle-lever 20 to exert a pressure on the plate 21, and the latter then compresses the coal in the compression-box 6, and that when said rod 22 is turned in an opposite direction it causes the plate 21 to rise or move away from the cake or block of compressed coal 32 within said compression-box.

It is to be noted that when the plate 21 is compressing the coal into a cake or block 32 those portions of the cake 32 between the rollers 12 are depressed by reason of the sagging of the apron 11 at the places due to the pressure of the plate 21 on the coal within the box 6, it being understood that the portion of the apron 11 which is beneath and between the sprocket-wheels 9 becomes taut when the compression of the coal is being effected and permits the sagging hereinbefore described to take place. When the pressure upon the coal within the box 6 is removed and the mechanism by which the flexible apron 11 is driven toward the coke-oven comes into action, the top of said flexible apron is stretched 35 and straightened, as indicated by full lines in Fig. 1, slightly lifting the compressed block of coal 32. The position of the apron 11 when the coal is being compressed is indicated by dotted lines in Fig. 1. After the coal within the box 6 is compressed the plate 21 is raised by rotating the rod 22 and by turning the rod 18, and thus raising the bridge-bars 19, secured thereto. The levers 15 are then operated and owing to the eccentrics 14 exert a pull upon the rods 16, and the latter then cause the sides 5 of the compression-box 6 to turn upon their pivots or hinges 4 and move away from the cake 32 in order to permit the latter to be easily removed from 50 the compression-box 6. The compression-box is then brought in alinement with the door of an oven 3, and the front 7 of said box is turned upon its hinge 8, so as to act as a bridge between the box 6 and oven 3, as indicated in dotted lines in Fig. 1. The plate or pusher 13 is then advanced toward the oven 3 by reason of the sprocket-wheels 9 and chains 10, it being understood that said sprocket-wheels may be driven by any one of 55 the well-known means now in use and that when the plate 13 is advanced it pushes the cake 32 out of the box 6 and causes it to enter an oven 3, as seen in dotted lines in Fig. 1. When a cake 32 is placed within an oven 3, the plate 13 is returned to its normal position, as seen in full lines in Fig. 1, and the operation hereinbefore described is repeated, it

being understood that the sides 5 of the box 6 are also returned to their normal positions, as seen in said Fig. 1, and before another 70 charge of coal is delivered to the box 6.

It is apparent that the depressions or concave portions 33 on the under side of a cake 32, and as seen in dotted lines in Fig. 1, permit the heat in the oven 3 to pass underneath 75 said cake 32, as well as over the top and around the sides thereof, thereby greatly improving the quality of coke produced from a cake 32 of compressed coal.

Crude oil, asphalt, or other suitable substances may be used to assist the binding of the particles of coal in a cake 32 when compressed.

Having thus described my invention, what I claim as new, and desire to secure by Letters 85 Patent, is—

1. In a device of the kind specified, means for compressing the coal and means for forming depressions on the lower side of the cake of compressed coal.

2. In a device of the kind specified, a compression-box, means for compressing the coal, and an apron upon which the coal is supported and which is adapted to be operated to discharge the compressed coal into an oven.

3. In a device of the kind specified, a compression-box, means for compressing the coal, an apron upon which the coal is supported and a pusher adapted to assist in discharging the compressed coal into an oven.

4. In a device of the kind specified, an oven, and means for feeding the fuel into the same, said oven and feeding means being situated side by side, and the portion of said feeding means supporting the fuel being movable 105 only within limits exterior to the oven.

5. In a device of the kind specified, an oven and a feeding device, said feeding device comprising a support for the fuel and a pusher, said support for the fuel being movable only within limits exterior to the oven, and said pusher being movable into the end portion of the oven.

6. In a device of the kind specified, an oven and a feeding device, said feeding device comprising a support, a pusher and a gate, said gate being adapted to enter the oven-doorway to form a bridge, and said support being movable within limits exterior to said oven and said pusher being movable into the end portion of said oven.

7. In a device of the kind specified, an oven and a feeding device having a flexible bottom supported at intervals and movable within limits exterior to said oven.

8. In a device of the kind specified, an oven and a compression-box situated side by side, the bottom of said compression-box being movable only within limits exterior to said oven, and a pusher movable with said bottom and movable into the end portion of said oven.

9. In a device of the kind specified, an oven and a compression-box having a flexible bot-

tom supported at intervals, said bottom being movable within limits exterior to said oven, and provided with a pusher movable therewith and into the end portion of said 5 oven.

10. In a device of the kind specified, means for compressing the coal, and means for forming channels or passages on the lower side of the cake of compressed coal.

11. In a device of the kind specified, a compression-box, hinged sides therefor, means for operating said sides, a front for said box which is adapted to be lowered to form a support for the coal when the latter is being dis-

charged into an oven, means carried by said 15 box for compressing the coal, and a pusher for said coal.

12. In a device of the kind specified, a compression-box, hinged sides therefor, an apron upon which the coal is supported, a front on 20 said box which is adapted to be lowered, a pusher, means for operating said hinged sides and means for compressing the coal.

JOHN HAUG.
